UNITED STATES PATENT OFFICE.

ARTHUR C. PRINCE, OF CHICAGO, ILLINOIS.

REGISTERING BANK.

Application filed February 18, 1924. Serial No. 693,414.

This invention relates to a coin bank, particularly to a registering coin bank wherein a registering mechanism is mounted, which indicates the number of coins inserted. It 5 has for one object to provide in connection with such a bank, having a registering mechanism, means for preventing the fraudulent operation of the registering mechanism without the insertion of a coin entirely into 10 the bank. In the form shown the bank is of such size as to be conveniently carried in the pocket. Other objects will appear from time to time throughout the specification and claims.

15 My invention is illustrated more or less diagrammatically in the accompanying drawing, wherein:

Figure 1 is an elevation of the registering side of the bank with parts broken away;

20 Figure 2 is a vertical cross section on an enlarged scale taken on line 2—2 of Figure 1;

Figure 3 is a horizontal cross section taken on line 3—3 of Figure 2;

25 Figure 4 is an elevation of a part of the casing broken away, showing a portion of the operating mechanism of the bank looking in the direction of the arrow in Figure 3 and looking through the coin slot;

30 Figure 5 is a vertical cross section taken on line 5—5 of Figure 3;

Figure 6 is a detailed perspective view on an enlarged scale showing the part which directly operates the recording mechanism;

35 Figure 7 is a view similar to Figure 3 showing in perspective the part which prevents fraudulent movement of the operating mechanism;

40 Like parts are designated by like characters throughout.

A is the casing of the bank. It is formed here by means of a plurality of parts which will not be described in detail as they form no part of the present invention. The bank

45 is provided on one side with an opening A¹ beneath which a numbered dial B is adapted to be rotated and through which numbers will show. The bank is slotted as at A² to permit the insertion of coins.

50 The numbered dial B is provided with an inwardly turned notched flange B¹. Lying in a pocket within the wall of the bank casing is an operating dog C. It is provided

55 with a downwardly depending pawl C¹ which engages with the upwardly extending notched flange B¹ on the dial B. At its

opposite end it is provided with an angularly positioned baffle plate C². The dog C is positioned within the bank so that its end carrying the baffle plate C² extends partially 60 across the open coin slot A² through which coins are inserted. Adjacent the pawl C¹ is a laterally extending projection C³. Upon this is positioned a return spring D. This spring normally holds the dog and pawl in 65 the position shown in full lines in the figures. The pocket within which the dog and pawl moves is sufficiently large to permit upward displacement of the pawl so that it may ride over the notches on the flange of 70 the dial B. It is normally held down, however, by means of the spring D¹.

The locking mechanism which prevents operation of the registering mechanism, except by the full insertion of a coin, includes 75

a locking lever E. This lever is positioned within a housing E¹ within the blank. It normally lies in the position shown in full

lines in Figure 3. It is provided with a laterally bent end E² which hooks into the 80

housing E¹ and is provided with a downwardly extending enlarged end E³ which constitutes a detent pawl. This pawl is normally in contact with the upwardly ex- 85

tending notches B¹ of the dial B as shown 85

particularly in Figure 2. The member E is mounted within the housing E¹ and is made of such material and shape as to have a spring action and by this action

it is yieldingly held against the outer 90

wall of the bank in the position shown in Figure 3 in full lines. It is, however, adapted to yield on pressure from the outside caused by the introduction of a coin

and to be sprung inwardly into the position 95

shown in dotted lines in Figure 3. The housing E¹ in which the member E is positioned is slotted as at E⁴, and this slot being

opposite the slot A² through the outer eas- 100

ing of the bank, it permits the coin to pass through it to the interior of the bank. Between the two slots the casing is forced up- 105

ward as at E⁵ so as to form a protecting pro- jecting member for the coin. This protecting mem- 110

ber might be formed by any suitable means but it is preferable to bend the floor of the housing E¹.

Although I have shown an operative de- 110

vice, still it is obvious that many changes in size, shape and arrangement of parts might be made without departing materially from the spirit of my invention; and I wish

therefore that my showing be taken as in a sense diagrammatic.

The use and operation of my invention are as follows:

- 5 The detent pawl is normally in the position shown in full lines in the drawing. In that position the registering dial cannot be rotated because in order to clear the notches the detent pawl would have to be 10 forced upward and this cannot be done, since it is located within a housing, to the top of which it already extends. The dial is therefore locked against rotation. When 15 a coin is inserted, it strikes a portion of the member carrying the detent pawl and forces it inwardly bending the entire pawl carrying member inwardly toward the center of the bank and moving it thus laterally out of contact with the notched flange B¹. 20 When the detent pawl is thus moved out of contact with the notched flange, it strikes the inner side of the housing E¹ and is there positively stopped. Continued pressure upon the coin will therefore push against 25 the portion C² of the dial operating pawl, and since that pawl is mounted to yield by reason of the spring which holds it, it will give laterally as pressure is continued upon the coin, and since the locking pawl has been 30 moved out of contact with the teeth on the dial, the coin will enter the bank and the indicating mechanism will be operated. When the coin has been inserted both the dial operating mechanism and the detent 35 pawl carrying member spring back into the position shown in full lines in Figure 2.

I claim:

1. A coin bank comprising a receptacle, having a coin opening in said receptacle, 40 in combination with a registering means, a member within said bank normally overlying a portion of said opening, and adapted to be moved by the insertion of the coin into said bank, thereby to move said registering means to register the insertion of the coin, and a second member within said bank adapted to engage said registering means and lock the same against movement, said member adapted to be contacted and moved 45 out of locking position by the insertion of said coin to permit movement of the registering means in response to the insertion of the coin.

2. A coin bank comprising a receiving 55 receptacle, provided with an opening, and in combination with said receptacle a registering device adapted to register the number of coins inserted, said registering device including a member normally overlying a portion of said opening, and adapted to be displaced by the insertion of a coin into said opening, and thereby to operate said registering device to register the insertion of the coin, said registering device comprising 60 a disc shaped member mounted within the

bank for rotation, provided with numbers adapted to be seen outside of the bank, having inwardly extending from its edges a plurality of notches adapted to be engaged by the first mentioned member and to be moved thereby, and a second member within said bank adapted to engage said registering means and lock the same against movement, said member adapted to be contacted and moved out of locking position by the insertion of said coin to permit movement of the registering means in response to the insertion of the coin. 75

3. In a bank having a coin slot, a registering mechanism adapted to register the coins inserted, including a plurality of numbers adapted to be progressively displayed as such mechanism is operated, in combination with a shutter adapted to be moved by the insertion of a coin to operate said registering mechanism, said shutter being mounted wholly within one wall of said bank, and a member within said bank adapted to engage said registering means and lock the same against movement, said member adapted to be contacted and moved out of locking position by the insertion of said coin to permit movement of the registering means in response to the insertion of the coin. 85

4. In a pocket bank having a coin slot, a registering mechanism adapted to register the coins inserted, including a circular dial pivoted for rotation within said bank, provided about its edge with an upturned flange in which a plurality of teeth are formed, in combination with a movable shutter concentric with said bank and mounted wholly in the wall thereof, and adapted to move in a path concentric with said bank, adapted normally to shut off a portion of said coin slot and provided with a downwardly depending portion adapted to engage the teeth of said dial, said shutter being adapted to be moved laterally by the insertion of a coin and in such movement through its downwardly depending portion adapted to engage one of the teeth of said dial, and to rotate the same to register the insertion of the coin, and a member within said bank adapted to engage said registering means and lock the same against movement, said member adapted to be contacted and moved out of locking position by the insertion of said coin to permit movement of the registering means in response to the insertion of the coin. 100 110 115

5. In a pocket coin bank, having a coin slot and a registering apparatus and means within the bank for operating said apparatus in response to the insertion of a coin, 125 said means including a shutter normally partially closing said slot, and locking means to engage a part of said registering mechanism to prevent its movement, said locking means adapted to be moved out of locking 130

- engagement with said registering means by the insertion of a coin, said registering means being free for operation in response to the insertion of a coin after the freeing movement of said locking means, and a guiding member within said bank adapted to guide the coin so as properly to operate the locking means and the registering operating means.
6. In combination in a coin bank having a coin slot and a registering mechanism, a mechanism for moving such registering mechanism in response to the insertion of a coin, a locking member adapted normally to lock the registering mechanism positively against movement, said registering mechanism including a shutter adapted normally to overlie such slot in part, such locking member lying within the normal path of a coin into the bank, such member being mounted so as to be contacted by the coin and deflected inwardly from its locking position by the inward movement of the coin, and guide means for directing the coin positively to contact such locking means.
7. In combination in a coin bank having a coin slot and a registering mechanism, a mechanism for moving such registering mechanism in response to the insertion of a coin, a locking member adapted normally to lock the registering mechanism positively against movement, said registering mechanism including a shutter adapted normally to overlie such slot in part, such locking member lying within the normal path of a coin into the bank, such member being mounted so as to be contacted by the coin and deflected inwardly from its locking position by the inward movement of the coin, a positive stop adapted to limit the movement of such locking member when moved out of locking position, and guiding means including a housing mounted within the bank through which the coin must pass and an inwardly inclined extension on such shutter.

Signed at Chicago, county of Cook, and State of Illinois, this 14th day of February, 1924.

ARTHUR C. PRINCE.
